DIAMOND HOLDING TOOL

Herbert Waldman, 1739 52nd St. 11204, and Joseph Waldman, 989 Montgomery St. 11213, both of Brooklyn, N.Y.

Filed Feb. 2, 1973, Ser. No. 328,901

Term of patent 14 years

In. Cl. D15—99

U.S. Cl. D54—13 A

FIG. 2

FIG. 1

FIG. 3

FIG. 4

FIG. 5

FIG. 6

FIG. 7

FIG. 1 is a front elevational view of a diamond holding tool, showing my new design;

FIG. 2 is an elevational view of one side thereof;

FIG. 3 is an elevational view of the other side thereof;

FIG. 4 is a top plan view thereof;

FIG. 5 is a rear elevational view thereof;

FIG. 6 is a bottom plan view thereof; and

FIG. 7 is a cross-sectional view thereof taken along line 7-7 of FIG. 1.

We claim:

The ornamental design for a diamond holding tool, substantially as shown.
